UNITED STATES PATENT OFFICE.

WILLIAM R. ROGERS, OF NEWARK, NEW JERSEY, ASSIGNOR TO WILLIAM RAUBITSCHEK, OF BROOKLYN, NEW YORK.

VIBRATORY NEEDLE MECHANISM.

1,250,511.

Specification of Letters Patent.

Patented Dec. 18, 1917.

Application filed May 1, 1916. Serial No. 94,729.

To all whom it may concern:

Be it known that I, WILLIAM R. ROGERS, a citizen of the United States, residing in the city of Newark, county of Essex, State of New Jersey, have invented a new and useful Improvement in Vibratory Needle Mechanism.

My invention relates more particularly to the automatic mechanism for producing a series of successive operative movements of the needle bar, and for repeating the same indeterminately.

Among other objects of my invention, may be specified the providing of a stitching mechanism adapted to sew a seam in a straight line for a measured interval, and then produce a determinate number of tie stitches and then continue stitching in a line parallel with the direction of the seam for a determinate interval, and again produce a determinate number of tie stitches and complete the operation by leaving the needle positioned to continue the seam on a projected line of the seam as illustrated in the drawings.

My invention is more particularly adapted to be used in a machine wherein the material is advanced forward in a straight line, for the stitching operation, and is fed to the machine in indeterminate lengths, and is particularly adapted for performing the stitching operation wherein a straight seam, having therein at measured intervals gaps of determinate width, is produced mechanically, by automatic means, in a continuous series of operations, including the production of tie stitches at the beginning and end of each gap.

A seam of the character described is useful among other things, to provide a fabric structure suitable for the mounting thereon, in operative position of a set of hooks and eyes, by engaging the mates of the pairs in the gaps thus provided, they being retained in position by their shanks, thus dispensing with the necessity for stapling hooks and eyes to the fabric, as is now done, and obviating the objectionable features of such method, familiar to those versed in the art.

Having thus generally described some of the objects and features of my invention, I will further and more particularly describe and specify the same, by reference to a machine which embodies my invention.

The construction of this machine is illus-

trated in the accompanying drawings, in which similar reference characters indicate identical parts.

Figure 1, is a side elevation of the sewing machine with parts shown in section, and with the guides for the fabric strips omitted.

Fig. 2, is an elevation of the front end of the machine, with the guides for the fabric strips in position.

Fig. 3, is an enlarged transverse section of the sewing machine on the line 3—3 of Fig. 1.

Fig. 4, is a similar view of the mechanism for continuing the normal reciprocatory motions of the feed bar, during the intervals in which it is not engaged with the material.

Fig. 5, is a sectional plan view of the same mechanism on the line 5—5 of Fig. 3, but with the feed bar in its normal operative position.

Fig. 6, is a plan view of two fabric strips united by a seam, having therein gaps or openings adapted to receive and engage the hooks and eyes by their shanks.

Fig. 7, is an enlarged transverse section of the same, on line 7—7 of Fig. 6.

Fig. 8, is a front elevation of the cam H H having but two recesses on its periphery.

Fig. 9, is a side elevation of the cam V V showing the angular sections in the groove v omitted, and the groove continued in straight section throughout.

Fig. 10, is a detail showing compression spring 12.

The stitch-producing mechanism of the sewing machine consists of a needle A, and the usual looping device B. The needle A, shown in Fig. 2, is secured in a needle bar C, mounted to reciprocate in an arm D, fulcrumed at its upper end, on the bracket arm E, of the sewing machine, as shown in said figure. By the arrangement described the arm D, and the needle bar C, and with it the needle A, can be vibrated laterally, relatively to the direction of the seam produced, that is from its normally vertical position to the right, relatively to the operator. The needle bar C, is reciprocated by the pitman F, which takes motion from the crank F¹, carried by the needle bar shaft F².

The needle bar C is normally retained in a vertical position, but may be operatively vibrated, or may be deflected to the right

and operatively retained in that position, and may also be again deflected and returned to its normal position as the automatic control of its varied stitching operations requires.

The vibrating mechanism is automatically controlled through a worm G^2 mounted on the needle bar shaft F^2 shown in Fig. 1, which intermeshes with a spur gear G^1 , 10 carried by the cam shaft G on which is detachably mounted the rotary cam H , as shown in Figs. 1, 2, and 3, which operatively is rotated in the direction of the arrow a . The rotary cam H , is provided with two 15 sets of recesses on opposite sides of the periphery of the wheel, as shown: each series are respectively lettered H^1 , H^2 and H^3 , as shown in Fig. 1.

The peripheral face of the cam H is engaged by a friction roller I , journaled on the free end of an arm I^1 pivoted, on the bracket arm E , to move laterally, and positioned by a tension spring I^2 indicated in Fig. 1, to normally engage the roller I , with 25 the peripheral face of the cam H , and to operatively engage the roller in the recessed sections. The arm I^1 is provided with a guideway I^3 , through which is adjustably secured the link J^2 , by the pivot pin J . The 30 link J^2 is adjustably engaged and secured by two screws J^5 for parallel adjustment to the link J^3 , to permit of positioning arm D . For the purpose mentioned, the part J^2 , is provided with an elongated slot J^4 , 35 through which extends screws J^5 , engaging the part J^3 to permit the lateral adjustment of the latter relatively to the part J^2 . In order to vary the amplitude of the vibratory motions of the needle bar C , the pivot 40 J is adjustably positioned in the guideway I^3 . The needle bar C is normally maintained in a vertical position by the engagement of the roller I , with the sections of the peripheral face of the cam H , intervening 45 between the above described series of recesses therein, on the opposite sides thereof. When the roller I engages in the recess H^1 , the needle bar C is deflected to the right, or laterally of the line of movement of the 50 material, and is timed to complete a downward reciprocation in that position; the disengagement of the roller I from the recess H^1 operatively returns the needle bar C to its normal position, and while in that position it completes a downward reciprocation. The engagement of the roller I in recess H^2 again deflects the needle bar C to the right and it reciprocates in such deflected position during such engagement. The disengagement 55 of the roller from recess H^2 again returns the needle bar to its normal position where it completes a downward reciprocation. The engagement of the roller I in recess H^3 again deflects the needle bar C 60 to the right, in which position it completes

a downward reciprocation, and the disengagement from the recess H^3 of the roller I , again returns the needle bar C to its normal position in which position it continues to reciprocate until the roller I is in due 70 course engaged in the next recess H^1 , when a similar series of operative motions of the needle bar C , are repeated. The oscillation of the shaft O gives motion to the feed bar N , and an up and down swinging motion is 75 given to the feed bar N by the usual mechanism, including, as shown, a hollow rock shaft P , having an arm P^1 , movably engaging a fork N^2 formed on the feed bar N . The shaft P is provided near its rear end with an arm P^2 , connected by an eccentric rod P^3 , with an eccentric P^4 mounted on the needle bar shaft F^2 , so that when the machine is operated, a continuous rocking motion is given to the shaft P which through 80 the arm P^1 , imparts an up and down swinging movement to the feed bar N . Through the hollow shaft P , extends the shaft B^1 , driving the looping device B and driven by pulleys B^2 , B^3 , and a belt B^4 , from the needle 85 bar shaft F^2 .

The rock shaft O , previously mentioned, is provided at its rear end with an arm O^2 provided with an elongated slot or guideway O^3 in which is movably mounted a slide Q 90 also engaging a guideway R^2 in a swinging arm R having its pivot R^1 journaled in a bearing formed on a bracket E^2 depending from the base E^1 . The arm R is pivotally connected with an eccentric rod S of an 95 eccentric S^2 , mounted on the needle bar shaft F^2 , so that the arm R is operatively caused to swing up and down and the swinging movement of the arm R is transmitted by the slide Q to the arm O^2 , to rock the shaft 100 O , and thus operatively engage the feed bar N , with the material. The slide Q is provided with a pivot pin Q^1 pivotally connected by a link T with one arm of the lever T^1 , fulcrumed at T^2 , on the under side of the 105 base E^1 , and connected by its other arm through a link U with one arm of a crank lever U^1 fulcrumed on one side of the arm E and carrying at its other end a friction roller U^2 , 110 engaging a groove v , in the peripheral face of a cam V , shown as detachably secured on the shaft G previously mentioned. The cam groove v is provided with angular offsets V^2 , V^4 , for imparting a reciprocal motion to the lever U^1 . During the time 115 the friction roller U^2 is traveling through the straight sections V^1 and V^3 of the groove v , in the cam V , the slide Q is held in the guideway of the arm R , at a sufficient distance from the axis of the arm to impart a 120 swinging motion through the slide Q to the arm O^2 , to rock the shaft O , as previously mentioned. When however, the friction roller U^2 , engages in the angular sections V^2 125 or V^4 of the cam V , then a reciprocal motion 130

tion is given to the lever U^1 , whereby a similar movement is given to the lever T^1 , so that by the engagement of the roller U^2 , in either of such angular sections V^2 or V^4 , the slide 5 Q is moved into a central position, relatively to the axis of the pivot R , rendering the slide Q and shaft O inoperative, during such engagement of the roller U^2 . When the roller U^2 emerges from either of the angular sections named, and is returned to either of the straight sections V^1 or V^3 , the lever T^1 , is thereby returned to its normal 10 position, and again imparts operative motion to the slide Q , and shaft O . The angular sections V^2 and V^4 of the cam V , are so arranged relatively to the recesses H^1 , and H^3 , on the cam H , that their related motions are so timed that when the cross stitches K^1 and K^3 are produced the operative motions 15 20 of the feed bar N cease, but during the time the rows of stitches K and K^2 are produced the friction roller U^2 travels in the straight sections V^1 and V^2 of the groove and the slide R is maintained at such a distance from 25 the center of the pivot R^1 , as to secure the imparting of a rocking motion to the shaft O , thus operatively reciprocating the feed bar N .

The link T , previously mentioned, is preferably made in two parts, T^3 , T^4 , adjustable one on the other to lengthen or shorten the link, and for this purpose the part T^3 is provided with an elongated slot T^5 , through which extend screws T^6 engaging the part 30 35 T^4 , whereby the proper adjustment of the pivot pin Q^1 and the slide Q to move the latter into axial alinement with the pivot R^1 , may be secured as previously explained.

The fabric strips L and L^1 pass through 40 45 suitable scrolls W , W^1 , attached to the base E^1 , on the front of the machine to double up the edges of the strips and to properly guide the same to the needle A , the feed bar N , and the presser foot X are of usual construction (see Fig. 2). The strips L and L^1 prior to reaching the scrolls W and W^1 , pass through tension devices W^2 and W^3 , and the strips are guided to the said tension devices over a guide rod W^4 . The interval between 50 55 the gaps are controlled by the distance between the recessed sections of the cam H , and the width of the gap is determined by length of the recess H^2 .

The operation of the machine is as follows:

The material is operatively fed to the machine in a straight line, by a constant forward motion, which is interrupted only when the feed is rendered inoperative during 60 65 the intermittent periods as hereafter explained. And the material is so positioned that the stitching operation shall produce a seam conveniently near the edge of the strip of fabric material, when the needle is normally positioned and reciprocating verti- 70 75 80 85 90 95 100 105 110 115 120 125 130

cally, and shall engage both the material of the strip and the body or base fabric, and unite them together as illustrated by the sections K K^2 in Fig. 6. The seam thus produced is continued for the measured interval, during which the friction roller I , is engaged with the peripheral face of the cam H , before reaching either recess H^1 . When the roller I , in due course engages in either recess H^1 , the lateral movement of the arm I^1 thereby permitted, operates to deflect the needle bar C to the right and simultaneously with the engagement of the roller I , in the recess, the feeding mechanism becomes inoperative, as heretofore explained, and the succeeding downward reciprocation of the needle A , produces a stitch at right angles to the line or direction of the seam K , then the roller mounts the peripheral section between the recess H^1 and the recess H^2 , thereby deflecting the needle in an opposite direction, and returning it to its vertical position. The material remaining stationary, through the lack of engagement, with it of the feed member N ; the needle is then reciprocated downward, making a second stitch in the same location, in the reverse direction. The needle bar C , as the roller I , descends into the recess H^2 , is again deflected to the right before the feed bar N is again engaged with the material, thus adding another tie stitch, and completing the operation of tie stitches. With the material properly positioned, the lateral deflection of the needle, to the right, while making tie stitches, carries it beyond the edge of the strip of fabric material, so that one end of the stitch engages with and unites both the fabric material and the body fabric, while the other end engages only in the material of the body fabric. Through the timing of the related motions of the cam H , with the cam V , the feed bar N , which had been so depressed, during the tie stitch operation, that it did not engage with the fabric material to advance or feed it forwardly to the needle, is again restored to operative position and engagement, and so remains while the roller I , is in its depressed position in the recess H^2 during which period a series of stitches are produced, which engage only with the body fabric, and which are so produced in a line parallel with the direction of the seam K . When the roller I mounts from the recess H^2 to the peripheral face of the cam H , it operatively returns the needle bar C to its normal position, while simultaneously therewith, the feed member N is again disengaged from the material and rendered inoperative, the stitch thus produced being at substantially a right angle, as the material remains stationary, and the needle bar C is reciprocated downwardly, producing a tie stitch, the inner end of which is on a pro-

jected line, identical with the section of the seam K, theretofore completed. When the roller I, descending into the recess H³ again deflects the needle bar C to the right, and 5 the needle is downwardly reciprocated in this position, adding another tie stitch, the outer end of which engages only with the body fabric, then the roller I, mounting from the recess H³ to the next intervening 10 section of the face of the periphery of the cam H again returns the needle reversely to its normal position, where the downward reciprocation of the needle adds another tie 15 stitch, completing the production of the tie stitches, at the end of the gap or opening, thus producing a gap in the seam, uniting the strip of fabric material with the body fabric. Simultaneously with the roller I again attaining the face of the periphery of 20 the cam H, the timing of the related motions of the feeding device and the vibratory mechanism, actuating the needle bar C, causes the operative reengagement of the feed member N, with the fabric material, 25 thereby resuming the forward advance of the material, continuously for the next measured interval, before the production of another gap or opening, with the attendant operations of inserting the required number 30 of tie stitches at the beginning and the end of the gap. The strip of fabric material is fed to the machine in indeterminate lengths, and the automatic production of a series of 35 gaps of determinate width, operatively continues, while the material is fed for that purpose.

Having thus specified and described my invention, and shown a machine wherein it is embodied, I claim as novel, and my invention:

1. In a sewing machine, an automatic stitch producing mechanism comprising, in combination, a needle bar, a frame fulcrumed for lateral vibratory motion in 40 which the needle bar is mounted to reciprocate, a needle bar shaft from which such needle bar is reciprocated, a rotary cam having a number of recesses, located diametri-

cally opposite each other, on its periphery, a worm gear through which the cam receives 50 motion from the needle bar shaft, a rock arm, a friction roller carried thereon engaging with such recesses in the cam and adjustable links connecting said rock arm with the lower end of the needle bar frame. 55

2. In a sewing machine, an automatic stitch producing mechanism comprising, in combination, a needle bar, a frame fulcrumed for lateral vibratory motion in which the needle bar is mounted to reciprocate, a needle bar shaft from which such needle bar is reciprocated, a rotary cam having a number of recesses on its periphery, located at such relative distances from each other as to adapt them to operatively deflect the needle bar, at timed intervals, to permit of the insertion in the material of an offset section of stitching with tie stitches at each end of such section, a worm gear through which the cam receives 60 motion from the needle bar shaft, a rock arm, a friction roller carried thereon engaging such recesses in the cam and adjustable links connecting such rock arm with the lower end of the needle bar frame. 65

3. In a sewing machine, an automatic stitch producing mechanism comprising, in combination, a frame fulcrumed at its upper end for lateral motion, a needle bar mounted to reciprocate therein, a needle bar shaft 80 from which such needle bar is reciprocated, a rotary cam, also receiving motion from such needle bar shaft having two groups of recesses on opposite diametrical faces of its periphery, each group containing recesses of unequal length, a friction roller mounted to operatively bear on the periphery of such cam, a lever fulcrumed at its upper end on which said roller is carried and which lever is operatively related to the needle bar frame 85 to control the lateral motions of the latter. 90
